UNITED STATES PATENT OFFICE.

ISAAC SHIMWELL McDougall, of Irk Vale, Chadderton, and THOMAS SUGDEN, of Oldham, County of Lancaster, Assignors of One-Third to JAMES THOMAS McDougall, of London, England.

STEAM-TRAP.

SPECIFICATION forming part of Letters Patent No. 368,101, dated August 9, 1887.

Application filed April 11, 1887. Serial No. 234,403. (No model.) Patented in England May 23, 1885, No. 6,350.

To all whom it may concern:

Be it known that we, ISAAC SHIMWELL McDougall, manufacturing chemist, and THOMAS SUGDEN, mechanical engineer in the employ of McDougall Brothers, subjects of the Queen of Great Britain and Ireland, and residing, respectively, ISAAC SHIMWELL McDougall at Irk Vale, Chadderton, near Manchester, and THOMAS SUGDEN at Greengate Street, Oldham, both in the county of Lancaster, England, have jointly invented certain new and useful Improvements in Steam-Traps or Apparatus for Separating Water or other Liquids from Steam-Vapors or Gases, (for which we have obtained a patent in Great Britain, dated May 23, 1885, No. 6,350,) of which the following is a specification.

This invention has for its object to provide a strong, effective, simple, and cheap steam-trap or apparatus for the separation of water or other liquids from steam-vapors or gases in such a manner as to effect the separation automatically, the said trap or apparatus being readily adjustable and being provided with an arrangement for testing the apparatus while at work for clearing the valve and seatings of dirt and grit and for the discharge of air.

We will describe the invention with reference to the accompanying drawings, which represent, in Figure 1, a section of an apparatus constructed according thereto, and in Fig. 2 a sectional elevation of a modified form of outlet-valve.

A is the vessel or casing in which the water accumulates, the said vessel having in its interior a fulcrum-pin, a^2 , carried by the standard a , or otherwise, on which fulcrum is mounted a lever, B, having at one end a piece, C, of light specific gravity, and preferably solid, which we will call a "float," and at the other end a piece, D, of greater specific gravity, which is also preferably solid, which we will call a "weight." Both the float and the weight are inclosed in the vessel A, and are preferably adjustable on the lever B. A valve, which is by preference an equilibrium or balanced stop-valve, E, is situated in the lower part of the vessel, and is provided with an outlet-passage, A^2 , which in the case of an

equilibrium-valve, as shown, is between the upper and lower members of the valve, for the convenience of outlet. The valve is connected to the lever B at the same end as that to which the float C is attached. The float C may be, with advantage, of a material such as earthenware. The float is counterweighted by the weight D, which may be, for example, of iron or lead. The vessel A is provided with a suitable inlet, A^3 . The position of the weight D and float C on the lever B is such as to keep the valve E closed when there is no water in the vessel A, or when there is only a predetermined amount of water therein—that is, the float exerts a greater pressure on the valve in one direction than the weight exerts in the other direction.

The float C and weight D are preferably so arranged that the float C only is immersed in the water in the vessel, the weight D being situated above the water-level, as shown clearly in the drawings. If steam only be admitted into the vessel, the valve is not affected, owing to the pressure of the steam acting on equal and opposite surfaces. When, however, water enters the vessel A, the valve E becomes immersed in water; but no action takes place until the water rises to a certain level, say, sufficiently high to nearly immerse the float C, which then loses its downward force and the opposed weight D raises the float, and with it the valve E, which then allows the water to be discharged through the outlet A^2 . This continues until the water has nearly left the float C, when the said float regains its power over the weight D, and consequently the valve E is again closed, although the valve is still immersed in water, so that the water is discharged without loss of steam.

A testing-rod, G, works through a gland or the like in the vessel A, the bottom part, g , of the rod inside the vessel when testing coming into contact with the lever, or, as illustrated, the weight D thereon for opening the valve E, for blowing off, and by this means the valve and seating are cleared of dirt without taking off the cover or detaching the valve or seating. A bracket, h , is fixed on the casing A, and is provided with a stop-peg, h^2 , and suit-

able holes are provided in the test-rod G, so that the valve may be kept open to allow the escape of air when steam is just turned in, so as to avoid excessive pressure due to expansion of air or gases.

The arrangement in Fig. 1 shows valves resting on seatings; but we do not limit ourselves to that form of valve. Fig. 2 shows a modification, in which piston-valves are used which are guided by the wing-pieces beneath.

Although we have described the apparatus as used for the separation of water from steam, it will be evident that it is applicable for the separation of liquids from vapors or gases generally.

Having now described and particularly ascertained the nature of our said invention and in what manner the same is to be performed, we declare that what we claim is—

The combination, with the vessel A, having 20 passage A², of the pivoted lever B, provided at opposite ends with weight D and float C, the outlet-valve connected to said lever, and the testing-rod G, under the arrangement and for operation as hereinbefore set forth.

In testimony whereof we have signed our names to this specification in the presence of two subscribing witnesses.

ISAAC SHIMWELL McDougall.
THOMAS SUGDEN.
